(57) **CLAIM**

The ornamental design for a garment bag, as shown and described.

DESCRIPTION

FIG. 1 is an isometric view of a garment bag, showing my design; and

FIG. 2 is a front view thereof;

FIG. 3 is a rear view thereof;

FIG. 4 is an opened interior view thereof; and,

FIG. 5 is an opened external view thereof.

The broken lines represent fold lines that form no part of the claim.

1 Claim, 5 Drawing Sheets
